KEY POUCH

Daniel Julius Nash, Jersey City, and Robert L. Hatfield, East Orange, N. J., assignors, by direct and mesne assignments, to Nash Inc., Jersey City, N. J., a corporation of New Jersey

Application August 3, 1948, Serial No. 42,266

4 Claims. (Cl. 150—40)

1

The present invention relates generally to key containers of the type comprising a pouch wherein the keys are normally disposed out of sight, the pouch having manually operable means therewith for ejecting the keys from the pouch into position for use. The present invention is an improvement over the key pouch of this general type as disclosed and claimed in our prior Patent No. 2,176,677, granted October 17, 1939, and relates to the specific means for ejecting the keys from within the pouch.

While the device of our prior patent has been very satisfactory, it has been found desirable to provide different means for actuating the key advancing mechanism. The main object of the present invention, therefore, is the provision of means, moving along a curved—rather than a straight line—path for actuating the key advancing mechanism. Our device comprises a pouch, open at its lower end, within which is contained a key supporting plate, advancing or extending means for the plate disposed within the pouch, and manually operable actuating means for the plate within the pouch, portions thereof extending outwardly of the pouch at the upper side ends thereof. Formerly, as in our prior patent, these portions were adapted to be reciprocated in a straight line path for actuating the extending means. Now, however, we propose to actuate these means along a curve thereby to reduce resistance to movement, and make the extension of the key plate more positive.

Another object of our invention is the provision of actuating means, in a device of the character described, pivoted at one end thereof, the other end being movable inwardly of the device along a curved path to operate the key plate extending means.

Still another object of the present invention is the provision, in a device of the character described, of key plate advancing or extending means comprising a pair of oppositely disposed, pivotally mounted finger pieces, moving towards each other along curved paths and downwardly in the direction of the line of advance.

In the drawings annexed hereto, and forming a part hereof,

Figure 1 is a part elevational, part vertical sectional view, of the operating portion of one form of key pouch constructed according to and embodying our invention;

Fig. 2 is a similar view thereof illustrating the advancing means in extended position;

Fig. 3 is a horizontal section through the device along the line 3—3 of Fig. 1;

2

Fig. 4 is a vertical section on the line 4—4 of Fig. 3;

Fig. 5 is a detail section on the line 5—5 of Fig. 1; and

Fig. 6 is a front elevational view of the device in normal, at rest, position with a portion of the pouch cut away to reveal the position of the keys and key plate inside the pouch.

The device, as a unit, comprises, a flat, thin key supporting plate 10, means to reciprocably advance same out of the enclosing pouch and back thereto, said means being indicated generally by reference numeral 12, and the pouch, indicated by reference numeral 14.

The pouch 14 may be formed of leather, fabric, plastic material or otherwise, as desired, either of two similarly sized and shaped pieces joined together at the top and along the side edges, or of a single piece folded along a vertical median line. The pouch is relatively thin, and is open as at 16 along its lower horizontal edge 18. A pair of openings 20, 20 are provided at the upper corners of pouch 14. The upper end of pouch 14 is indicated by reference numeral 22.

Inside pouch 14, and along the upper edge thereof is secured a receptor plate 30, of inverted U-shaped in section, fastened to pouch 14 as by glue, rivets or otherwise. Plate 30 may be formed of thin, light gauge metal, as by stamping or otherwise, and has a flat rear wall component 32, a front wall 36, and an intermediate bridge piece 34 located against the upper inner edge of the pouch.

A pair of hollow finger pieces 40, 40 are mounted on receptor 30 between walls 32, 36, for pivotal movement, as follows: Each finger piece 40, which may be stamped of light gauge metal, or formed of some plastic material as desired, comprises an outwardly curved enlarged head portion 42 at the top thereof which normally extends out of the pouch corner openings 20, 20 beyond the marginal edges of the pouch, and a narrow leg portion 44 extending downwardly therefrom reaching between walls 32, 36 adjacent their lower edges, as by means of outwardly bent lugs

46, 46 fitted into sector shaped openings 48, 48 in the walls 32, 36. Lugs 46, 46 are relatively short, flat and straight, and their movement in slots 48, 48 is limited by the upper and lower marginal walls of the sector openings.

The reciprocating key plate moving means 12 comprise a lazy tongs system of links, made up of a plurality of pairs of similarly sized and shaped straight links 50, 50, pivotally connected as by rivets 52, 52 midway of the length thereof. The

ends of each pair of links are pivotally connected to the ends of the adjacent link pairs, as by rivets 54, 54. While in the present embodiment of our invention, three pairs of links 50, 50 are shown, more or fewer pairs may be used. The terminals 58, 58 of the uppermost pair of links 50, 50 are pivotally connected to the inner and upper reaches of the finger pieces 40, 40, as by pins 60, 60 extending through aligned openings in pieces 40, terminals 58 (see Fig. 3) and through hollow spacing tubes 62, 62.

The terminals 70, 70 of the lowermost pair of links 50, 50 have pins 72 and slot 74 connections with the upper end of the key supporting plate 10, as shown in Fig. 1. Plate 10, at the lower edge 76 thereof, is provided with a plurality of key holding loops or clips 78, 78 from which keys, as 80, may be suspended. Means are provided to contract the lazy tongs system within pouch 14, which consists of a spring 82, having a centrally formed helical coil 84, the free ends 86, 86 of the spring terminating in hooked fingers 88, 88 pivotally connected to rivets 54, 54 of adjacent link pairs (see Fig. 2). This construction normally draws the links of the lazy tongs system together, bears key plate 10 with keys 80 thereon into pouch 10, and in like manner urges the heads 42, 42 of finger pieces 40, 40 to extend outwardly out of the corner openings 20, 20 while defining the limit—with sector openings 48—of movement.

When it is desired to extend the key plate 10 out of pouch so as to expose keys 80 for use, finger pieces 40, 40 are pressed towards each other against the normal tensioning of the spring 82. Pivoting about lugs 46, 46 in openings 48, 48, the finger pieces move inwardly, along a curved path, as in Figure 2, and downwardly in the direction of extension of the lazy tongs system. The sides of the arc of sector openings 48, 48 limits the extent of inward movement of the finger pieces, the length of such movement being such as to ensure the extension of the lower edge of plate 10 slightly beyond the pouch opening 16, at the lower end 18 thereof.

Means are provided for holding the tongs system under extension, these means comprising an enlarged button 90 extending forwardly of the central pivot of the uppermost pair of links outwardly of receptor plate 30 through a vertically extending slot 92 in front wall 36 thereof, and a rocking detent plate 94 mounted on the front face of wall 36. The lower edge 96 of plate 94 is normally urged, by a spring 98 trapped beneath the upper edge 100 of plate 94 and between it and wall 36, inwardly towards the wall. As button 90 moves downwardly with the lazy tongs system, it moves underneath and lifts edge 96, and rides past the same, edge 96 of the plate dropping against wall 36 when button 90 has cleared. Edge 96 will thereupon act as a stop to prevent button 90 from returning up slot 92, holding the tongs system in extension. In order to release the tongs, for return into pouch 10, the opposite end 100 of rocking plate 94 is pressed inwardly against the biasing of spring 98, raising the lower edge 96 and permitting the return movement under the influence of coil spring 84.

Having described our invention, what we claim and desire to secure by Letters Patent is:

1. A key pouch comprising a generally rectangular casing having an opening across the full width thereof at the lower end, a pair of openings at the upper corners of the upper end of the case, a key supporting plate, ejecting mechanism therefor within the case, the ejecting

mechanism including a lazy tongs system of links comprising a plurality of pivotally connected pairs of pivotally connected links, the plate being connected to and movable with the lower end of the lazy tongs system, actuating means for said system to move the plate toward and away from the first mentioned opening and project and retract keys on the plate out of and back into the case through said opening, said actuating means including a spring normally urging the links in one direction, and finger pieces pivotally connected by one end thereof to the upper end of the links for actuating same against the influence of said spring, the other end of the finger pieces being pivoted about a point spaced from said connected end.

2. A key pouch comprising a generally rectangular casing having an opening across the full width thereof at one end, a pair of openings at the upper corners of the opposite end of the case, a key supporting plate and ejecting mechanism therefor disposed and secured within the case, the ejecting mechanism including a lazy tongs system of links composed of a plurality of pivotally connected pairs of pivotally connected links, the plate being connected to and movable with one end of the lazy tongs system, actuating means for said system to shift the plate toward and away from the first referred to opening, and project and retract keys on the plate out of and back into the case through said opening, said actuating means including a spring normally urging the links in one direction, and a pair of finger pieces rotatably connected at one end thereof to the links for actuating same against the normal biasing of said spring, the said end of the finger pieces being movable towards each other along an arcuate path downwardly in the direction of the ejecting movement, the other end of each of said finger pieces pivoting about a point spaced from the link-connected end thereof.

3. A key pouch comprising a generally rectangular casing having an opening at one end thereof across the full width of the case and a pair of openings at the upper corners of the opposite end of the case, a receptor plate secured inside the casing adjacent the upper end thereof, a key supporting plate and ejecting mechanism therefor reciprocably disposed within the case, the ejecting mechanism including a lazy tongs system of links comprising a plurality of pivotally connected pairs of pivotally connected links, the key supporting plate being connected to and movable along with one end of the lazy tongs system, actuating means for said system to move the plate toward and away from the first opening and project and retract keys on the plate out of and back into the case through said opening, said actuating means including a spring normally urging the links in one direction, and finger pieces on the receptor plate pivotally connected at one end of the said pieces to the links for actuating same against the influence of the spring, the other ends of the finger pieces pivoting on the receptor plate about a point spaced from the link-connected ends of said finger pieces.

4. A key pouch comprising a generally rectangular casing having an opening across the full width of the case at the lower end thereof, a pair of openings at the upper corners of the case at the upper end thereof, a receptor plate disposed inside the casing at the upper end thereof, a key supporting plate and ejecting mecha-

nism therefor disposed within the case connected to the receptor plate, the ejecting mechanism including a lazy tongs system of links comprising a plurality of pivotally connected pairs of pivotally connected links, the key supporting plate being connected to and movable with one end of the lazy tongs system, actuating means for said system to move the plate toward and away from the first opening and project and retract keys on the plate out of and back into the case through said opening, said actuating means including a spring for actuating the links normally in one direction, and finger pieces normally projecting out of the corner openings, swingably mounted on the receptor plate, one end of each of the finger pieces being connected to the links for actuating same in the direction against the normal biasing of said spring, the other ends of the finger pieces swinging about a point spaced from the link-connected ends of the finger pieces, said finger pieces on pivoting thereof moving inwardly towards each other and downwardly along a

curved path toward the open lower edge of the case.
